UNITED STATES PATENT OFFICE.

GEORGE WILLIAM REHFELD, OF MANHATTAN, KANSAS.

SILT ACCUMULATOR.

Application filed June 25, 1925. Serial No. 39,535.

This invention which may be termed a silt accumulator, is a device designed for use in silt bearing streams to check the flow of water and to prevent the banks of the streams 5 from washing away.

Heretofore, devices of this character have always been made of angle iron bars, channel-iron bars, and other kinds of rigid or non-yieldable bars, so that the devices have 10 always been applicable only to non-navigable streams and it has not been possible for them to be used in navigable streams because their rigid and non-yieldable formation has always caused damage to boats.

The present invention has been devised in order to provide a silt accumulator capable of being used in navigable streams. The improved device is constructed in such a way that it will yield when struck by a 20 boat without damaging the boat and will then spring back to normal position.

The invention is more particularly described with reference to the accompanying drawing which forms a part of this specification, and in which:

Fig. 1 is a perspective view of a device constructed in accordance with the invention;

Fig. 2 is a horizontal sectional view of the 30 device illustrated in Fig. 1;

Fig. 3 is a detail view illustrating the manner in which the various strips of the device may be tied together;

Fig. 4 is a view illustrating one of the tie 35 wires before it is bent around any of the strips of the device;

Fig. 5 is a perspective view of either another embodiment of the invention or else the principal framework of the device shown 40 in Fig. 1 with the bracing strips omitted;

Fig. 6 is a view similar to Fig. 5 showing diagonal strips applied to one side of the device shown in Fig. 5; and

Fig. 7 is a side elevation showing a further 45 form of construction.

As illustrated in the drawing, the device is in the form of a multi-sided skeleton frame composed of a plurality of yieldable strips which are tied together in crossed relation 50 forming yieldable arms extending from the sides of the frame. The strips out of which the device is made may be made of any suitable material, but they are preferably formed from lengths of spring steel or wire cable 55 composed of spring steel.

The multi-sided skeleton frame above alluded to, composed of yieldable strips or lengths of wire cable, may be formed as shown in Fig. 1 or as shown in Fig. 5, or in many other ways. Referring first to Fig. 5, 60 it will be seen that the frame is composed of three strips or lengths of cable 1 arranged in the form of a tripod, and also of three more strips or lengths of cable 2 connecting the lower ends of the strips 1. At the points 65 where the strips 1 and 2 cross one another, they are tied together, so that this particular frame has four triangular-shaped sides, each of which is bounded by three of the strips or lengths of cable.

Various means may be used for tying the strips or lengths of cable together. For this purpose, tie wires 3 may be used. Initially 70 these wires 3 may be U-shaped and after the strips or lengths of cable have been relatively 75 arranged in crossed relation, they may be passed around the adjacent strips or lengths as shown in Fig. 3.

The various strips are tied together in such a way that yieldable arms 4 will extend 80 from the corners and sides of the frame. Then, if pieces of cable are used, the cable strands at the ends of the arms 4 are unraveled and bent backwardly as indicated by the numerals 5. These portions 5 form pads 85 at the ends of the arms 4 to prevent damage to boats striking against them and also form claws to embed in the bed of a stream similar to the roots of a tree to anchor the device to the bed of a stream.

Where the device is large, additional strips or lengths of cable 6 may connect the strips or lengths 1 and 2 which bound each of the sides of the frame. In Fig. 6, three of the bracing strips 6 are shown applied to one 90 of the sides of the frame, while in Fig. 1, three of the bracing strips 6 are shown applied to each of the four sides of the frame. Fig. 7 discloses nine of the strips 6 for each side of the device. Any desired number may 95 be used. The ends of the strips 6 extend beyond the sides of the frame and form arms 7, and at the ends of these arms, if cable is used, the cable may be unraveled and bent 100 backwardly as at 8 to form the pads and claws corresponding to the pads and claws 5 formed at the ends of the arms 4.

In making use of the invention, a number of the skeleton frames are arranged in a line along the bank of a silt bearing stream, 110

or arranged in a line extending from the bank of a stream out into the stream. The frames, being constructed the same on all sides, may be set up upon the bed of the stream on any side, and the arms at the base will become embedded in the bed of a stream and hold the device anchored to the bed of a stream. The other arms and claws will catch drift, and in that way the devices will not only prevent washing away of the banks of the stream, but will actually build up such banks.

Inasmuch as the frame is composed of yieldable strips or lengths of flexible material, and the ends of the arms 4 are formed into pads, the device may be used in navigable streams as it will not damage boats striking against the same. Furthermore, in case any part of the device should be temporarily deflected out of shape by drift wood or floating ice, or the like, it will immediately spring back into its normal shape upon being disengaged by such obstruction.

From the foregoing description taken in connection with the accompanying drawing, the construction, use and advantages of the invention will be readily understood, so that further explanation is not necessary.

Various changes in form, proportion, and in various of the details of construction may be made without departing from the spirit and principle of the invention, and without sacrificing any of the advantages thereof, so that it is to be understood that such may be

done within the meaning and scope of the appended claims.

I claim:

1. A device of the class described comprising a skeleton frame composed of a plurality of strips and having four triangular-shaped sides, each bounded by three of such strips, and other strips connecting and bracing the strips which bound each side of the frame all of said strips having yieldable extremities projecting laterally beyond their longitudinal planes.

2. A device of the class described comprising a frame structure, arms projecting therefrom, and lateral claws projecting from and beyond the longitudinal plane of the arms.

3. A device of the class described comprising a frame structure, and arms formed of wire cable and projecting from said frame structure, the cable strands at the ends of the arms being unraveled and bent laterally to provide claws.

4. A device of the class described comprising a length of wire cable having an unraveled end whose strands are bent laterally to provide claws.

5. A silt accumulator comprising crossed inter-connected yieldable metal strips and yieldable claws arranged at the ends of and beyond the longitudinal planes of the strips.

In testimony whereof I have hereunto affixed my signature.

GEORGE WILLIAM REHFELD.
